UNITED STATES PATENT OFFICE.

ANDREW J. SANFORD, OF NEWARK, OHIO, ASSIGNOR TO A. H. HEISEY & COMPANY, OF NEWARK, OHIO.

DESIGN FOR A SHELF-SUPPORT.

46,753.

Specification for Design.

Patented Dec. 8, 1914.

Application filed September 16, 1914. Serial No. 862,109. Term of patent 14 years.

To all whom it may concern:

Be it known that I, ANDREW J. SANFORD, a citizen of the United States, and residing at Newark, in the county of Licking, State of Ohio, have invented a new, original, and ornamental Design for a Shelf-Support, of which the following is a specification, reference being had to the accompanying drawing, forming a part thereof.

The figure is a perspective view of a shelf support, showing my new design.

I claim:

The ornamental design for a shelf support, as shown.

ANDREW J. SANFORD.

Witnesses:

GEO. E. GRAESER,
MYRTLE E. GORBY.
